DRY MOPS

Sally N. Brown, 1025 5th Ave., New York, N.Y.
Filed Sept. 18, 1963, Ser. No. 309,633
6 Claims. (Cl. 15—228)

This invention relates to improved cleaning mops of the type known as "dry mops" for floors, walls and ceilings.

The various embodiments of the inventive concept have particular advantage for maintaining vinyl and other tile flooring between washings and/or waxings.

Cleaning mops having designs too numerous to catalogue have been in use from the very beginning of recorded history. Presently for our type of household civilization, the one mop design which has received large scale general acceptance is the type having a large plurality of fabric "strings" attached to the underside of a mop head, the latter being pivotally connected to a handle. The theory of operation of such a mop head is that the "strings" pick up dirt and dust from the floor when a dusting motion is applied to the mop head and the picked up dirt and dust can be released by shaking the mop head out of a window. Actually, such a mop head moves around and spreads as much dirt and dust as it picks up so as to merely give a false clean appearance. In any case, the "strings" become dirty since they can never release all of the dirt and dust which they manage to pick up and the storage of such a mop is unpleasant to both sight and smell. Furthermore, and very important, it is generally illegal today to shake mops out of windows in populated areas.

Admittedly, patent offices throughout the world have been deluged, particularly in the last 50 years, with new mop designs to replace the accepted "string" type mop with other mops having removable and able to be laundered fabric covers. However, none of such new designs have received large scale acceptance because of the disadvantages inherent in such designs with the result that general usage of "string" type mops still prevails.

Broadly speaking, it is an object of this invention to provide an improved cleaning mop for general large scale acceptance which will not have the disadvantages of the prior art designs, including the "string" type mop.

According to the invention there is provided a mop head comprising a frame member; a handle connector pivotally connected to the frame member; a substantially rectangular body member supported upon the frame member and having a resilient cushion bottom surface; and a soft enveloping mop cap member disposed over said body member; said mop cap member being longer along its side edges than said body member, closed along its two side edges and its front edge, and open along its rear edge to permit said mop cap member to be positioned upon and removed from said body member; said mop cap member having a longitudinal slit along its top surface extending from its rear edge, the edges of said slit enveloping said handle connector.

Other objects and features of the present invention will be set forth or apparent in the following description and claims and illustrated in the accompanying drawings, which disclose by way of example, and not by way of limitation, in a limited number of embodiments, the principle of the invention and structural implementations of the inventive concept.

2

In the drawings, in which like reference numbers designate like components in the several views:

FIG. 1 is a plan view, partly in cross section, of one embodiment of a mop head according to the invention;

5 FIG. 2 is a cross sectional view taken along line 2—2 of FIG. 1;

FIG. 3 is a perspective view, partly in cross section, of the mop head shown in FIGS. 1 and 2;

10 FIG. 4 is a bottom and rear end perspective view, partly in cross section, showing another embodiment of the mop head employing a plurality of mop caps according to the invention; and

15 FIG. 5 is an elevation view of the bottom of the mop head of FIG. 4 in a vertical storage position showing the exterior mop cap folded upon itself so that the dirty bottom surface of the exterior mop cap is not exposed.

As shown in FIGS. 1 and 2, a mop head comprises a one piece wire frame 10 having a substantially rectangular overall shape with straight side edges 12, 12' each terminating rearwardly in separate spaced back loop portions 14, 14'. The wire frame is bent to form spaced front curved portions 16, 16', the latter being connected by internal inwardly directed portions 18, 18' to form a central transverse straight portion 20. A handle connector 22 has a bent over portion 24 for pivotal connection to portion 20 of frame 10 and a socket 26 for connection to a handle 28.

20 A substantially rectangular body member 30, having an aperture 32 in the top surface thereof through which the handle connector 22 extends, envelops frame 10. A resilient cushion member 34, such as sheepskin with its natural wool face, is attached to the bottom surface of the body member 30. Advantageously, the resilient cushion member 34 is provided with a free end 35 which extends 35 rearward beyond the rear end 33 of the body member 30 for the reasons to be explained later.

25 A soft mop cap member 40, best shown in FIGS. 1, 2 and 3 is snugly fitted over the body member 30, the mop cap member being a rectangular glove or sack with closed sides 42, 42', a closed front edge 44 and an open rear portion 46 so that the mop cap 40 can be positioned upon and removed from the body member 30 to permit laundering as the mop cap becomes soiled. Mop cap 40 is somewhat longer than the bottom cushion member 34 so as to keep the latter covered and clean as the mop is moved in sweeping backward and forward movements. In order to accommodate the handle connector 22, the top surface of the mop cap 40 is slit to form adjacent longitudinal edges 48, 48' which extend from the open rear portion 46 to and around the handle connector 22. Advantageously, the handle connector 22 can have a notch 47 so that the spreading of the longitudinal edges 48, 48' in the rear half of the mop cap can be minimized.

30 Mop cap 40 is preferably fabricated from a one piece substantially rectangular finished edge fabric member having a base and a looped cotton pile. Such material is generally known as "toweling" or "terry cloth." However, other materials, including plastics, may be used.

35 Mop cap 40 is preferably fabricated by twice longitudinally folding the one piece fabric member to temporarily form a double open ended bag member with two closed sides 42, 42'. The two longitudinal edges 48, 48' are brought together in over-lapping relationship and stitches 50 (see FIG. 2) spaced from the edges 48, 48' are made

for a distance extending linearly from the front edge 44 of the mop cap 40 rearwardly towards the position which will be occupied by the handle connector 22, and in particular the notched portion 47 thereof. The double open ended bag member so formed is then closed at the front edge by stitches 54 after the line of stitches 50 is centrally and longitudinally located along the top surface of the mop cap 40.

Mop cap 40, is selectively dimensioned so that it fits rather snugly over the body member 30 (and the frame member 10) and optionally in a manner to slightly compress the resilient cushion bottom surface 34 of the body member 30. In any case, there is no need to employ snaps, pins or buckles to hold the mop cap 40 upon the mop head especially when toweling or terry cloth fabric is used. Also, with the preferred fabrication of the mop cap 40 as shown in FIG. 3, the longitudinal edges 48, 48' rearward of the handle connector 22 will tend to lie either very close to each other or in over-lapping relationship as a result of the stitches 50 which provide that the sum of the lengths of the two separate rear edges of the top surface of mop cap 40 is greater than the length of front edge 44.

A particularly advantageous embodiment appears in FIG. 4 wherein a plurality of mop caps 60, 70 are placed over mop cap 40 in interfitting or "piggyback" relationship. When each mop cap 40, 60 and 70 is substantially identical in size and shape the outer mop cap 70 determines the maximum outside dimensions of the mop head and the resilient cushion bottom member 34 can compress, if necessary, to accommodate the material of the inner mop caps 60 and 40 as well as a small amount of folding thereof.

Furniture which is encountered with forward sweeps of the mop head of FIG. 3 or 4 is protected from marring by the bridged unsupported stretched length of the body member 30 and the mop cap 40 between the two front loops 16, 16', the wire frame receding therefrom to form a "soft notch." On sweeping backward motions, furniture is protected from being marked as a result of the rearward over-hang of the resilient cushion member 34 beyond the two rear loops 14, 14', the latter being spaced to also form a rear "soft notch." Further, as furniture is encountered, the rearward over-hang portion will swing upwardly to completely cushion the wire portions 14, 14'. Furniture is protected from the side wire portions 12, 12' as a result of the springiness of such long straight side portions enhanced by the lack of a complete back edge as a consequence of the spaced rear loops 14, 14'. Added springiness to the side wire elements 12, 12' are provided by the rounded shape of the front wire loops 16, 16'. Optionally, a thick soft material for mop cap 40 will offer additional protection to prevent marring of furniture.

As the bottom surface of the mop cap 40 becomes soiled, it can easily be removed and laundered. Shrinkage of the mop cap material will not be seriously disadvantageous since the resilient cushion bottom surface 34 can accommodate changing dimensions.

When a plurality of mop caps are employed, only the bottom surface of the exterior cap will become soiled with use of the mop. As the external mop cap becomes dirty, it can be peeled off for laundering and the next innermost mop cap is ready for cleaning immediately.

When the exterior mop cap is only partially dirty so that it becomes convenient to store the mop without laundering the dirty mop cap, the rearward half of the exterior mop cap, shown as 70 in FIG. 5, can be folded back over the front half. When this is done, the entire dirty bottom surface of the exterior mop cap 70 is folded into itself and no part of the dirty bottom surface is exposed to view.

The mop caps, particularly when fabricated from toweling material or "terry cloth" can be made very attractive by employing colors and patterns so as to brighten up the cleaning chore and relieve the housewife from the

usual cleaning drudgery. Also, it has been found that toweling material or "terry cloth" is a very effective dirt and dust pick-up medium which far surpasses the cleaning power exhibited by the "string" type mop. The dirt and dust pick-up property of toweling or "terry cloth" mop caps is further improved when a plurality of mop caps are interfitted in "piggyback" manner of FIG. 4. It is believed that the slight relative motions of the plurality of the mop caps 40, 60, 70 generate static electricity which improves the dirt and dust pick-up effectiveness of the mop cap according to this invention.

While there has been described and pointed out the fundamental novel features of the invention as applied to preferred embodiments, it will be understood that various omissions and substitutions and changes in the form and details of the devices illustrated and its operation may be made by those skilled in the art, without departing from the spirit of the invention. It is the intention, therefore, to be limited only as indicated by the scope of the following claims.

What I claim is:

1. A cleaning mop of the character described comprising: a substantially rectangular resilient frame; a handle connector pivotally connected to the central section of said frame, said handle connector being provided with a socket in which a mop handle is adapted to be removably secured; a rectangular fabric body member which tightly envelopes said frame, an aperture in the top wall of said body member through which said handle connector extends; a relatively thick soft fuzzy resilient cushion member secured to the bottom wall of said body member, said cushion member being provided with a free end which extends rearwardly a substantial distance beyond the rear end of said body member; an enveloping bag-shaped cap member which is removably disposed about said body member and the said free end of said cushion member, the rear end of said cap member being open and the top wall thereof having a longitudinal slit which extends from the rear end thereof to substantially the mid-section thereof to permit the application of said cap member to said body member and the removal thereof from said body member.

2. A cleaning mop of the character described comprising: a substantially rectangular resilient frame formed from a single length of spring wire and comprising a pair of longitudinally extending spaced parallel side sections, the rear end of each of said side sections being formed into a loop, the forward ends of said side sections being bent inwardly into semi-circular sections and connected to a pair of spaced re-entrant sections which terminate substantially mid-way between the said loops and said semi-circular sections and are connected together by a transverse section; a handle connector pivotally connected to said transverse section, said handle connector being provided with a socket in which a mop handle is adapted to be removably secured; a rectangular fabric body member which tightly envelopes said frame, an aperture in the top wall of said body member through which said handle connector extends; a relatively thick soft fuzzy resilient cushion member secured to the bottom wall of said body member, said cushion member being provided with a free end which extends rearwardly a substantial distance beyond the rear end of said body member; an enveloping bag-shaped cap member which is removably disposed about said body member and the said free end of said cushion member, the rear end of said cap member being open and the top wall thereof having a longitudinal slit which extends from the rear end thereof to substantially the mid-section thereof to permit the application of said cap member to said body member and the removal thereof from said body member.

3. A cleaning mop as defined by claim 1 in which the open rear end of said cap member is spaced rearwardly from the free end of said cushion member.

4. A cleaning mop as defined by claim 1 in which said

- cap member is dimensioned to compress said resilient cushion member. 2,669,741 2/54 Jelliffe 15-229.2
 2,690,661 10/54 Briggs 15-229.1 XR
5. A cleaning mop as defined by claim 1 in which said cap member is fabricated from terry cloth. 2,815,521 12/57 Winckler 15-247 XR
 2,831,207 4/58 Thompson et al. 15-228
6. A cleaning mop as defined by claim 5 in which said 5 3,166,775 1/65 Cushman 15-228
 cushion member is fabricated from sheepskin.
